UNITED STATES PATENT OFFICE.

JOHN L. KOLBE, OF WAUWATOSA, WISCONSIN.

TAG HOLDER.

Application filed September 30, 1920. Serial No. 413,678.

To all whom it may concern:

Be it known that I, JOHN L. KOLBE, a citizen of the United States of America, residing at Wauwatosa, in the county of Milwaukee and State of Wisconsin, have invented new and useful Improvements in Tag Holders, of which the following is a specification.

The object of the invention is to provide a simple and efficient construction of holder or clip for use in attaching directions and identifying tags to fabrics and other articles designed for shipment or display, such as sacks or bags of merchandise, bales of goods having fabric wrappers or coverings and the like, and also adapted for attachment to the handles and wire reinforcing rings of buckets, cans, and similar receptacles; and more especially it is the object of the invention to provide a tag attaching device which is proof against accidental displacement or disengagement through the handling to which packages and like articles are subjected in shipment and storage with a view to minimizing the loss and inconvenience incident to an absence of identifying means; and with these objects in view the invention consists in the construction and combination of parts of which a preferred embodiment is shown in the drawings, where-in:

Figure 1 is a view of a tag holder arranged in the operative position in engagement with a sack or like container and supporting an identifying tag.

Figure 2 is a detail side view of a tag holder.

Figure 3 is a longitudinal section of the same.

Figure 4 is an end view.

Figure 5 is a side view of a tag holder with the sides deflected as in the operation of engaging the jaws thereof with the fabric wrapper or container.

Figure 6 is a view of a modified construction.

The holder in general form constitutes a loop 10 constructed of a single blank of wire of any suitable gage and having a reasonable degree of resilience or spring action, the closed end of the loop serving for engagement with the tag 11, while at the free ends of the arms 12 thereof are formed jaws 13 for engagement with the material

of the sack, or with any other objects such as a bale or handle or other available portion of a bucket, can or like receptacle.

In the construction illustrated in Figures 1 to 4 inclusive each jaw is of parallel sided looped form disposed transversely with relation to the body loop or length of the holder, with the outer side of each jaw loop deflected transversely from the plane of the body portion of the holder to cause the jaws to interlock transversely. In other words the sides of each jaw are disposed in a plane oblique to the plane of the holder or the body loop forming the holder, said oblique planes of the two jaws being in intersecting relation so that the inner and outer sides of each jaw operate respectively at opposite sides of the corresponding elements of the other jaw. When the holder is to be applied to an article such as the fabric container of a package or a sack composed of burlap or like material the sides of the body loop are pressed toward each other as indicated in Figure 5 until the free ends of the outer sides of the jaws are disengaged to permit said free ends to puncture or pass through the fabric, and upon release of the holder the movement in opposite directions by the jaws will confine a substantial portion of the fabric between the interlocked outer and inner sides of the jaws which by reason of their interlocked relation are secured against relative deflection. When the holder is closed or the jaws at the free ends of the arms thereof are interlocked as indicated, deflection of either arm of the body loop in a direction perpendicular to the plane of the loop is impossible, and therefore the disengagement of the holder from the fabric with which the jaws are engaged by the application of strain to the tag or to the looped portion of the holder is prevented except by applying thereto a strain sufficient to tear the fabric.

The lengths of the inner and outer sides of the loops forming the interlocking jaws are preferably substantially equal so that when the sides of the body loop are in their normal positions, the extremities of the outer sides of the jaws are substantially flush or co-incident with the looped or closed portions of the jaw loops, as indicated in Figure 2.

In the modified construction illustrated

in Figure 6 the main difference resides in the fact that the inner sides of the jaws 13^a are not parallel with the outer sides thereof but are disposed diagonally as indicated at 5 15 so that the inner sides of the two jaws intersect at a considerable distance from the transverse line of the outer sides of the jaws, but in the matter of the crossing of the elements so as to dispose the outer sides of 10 the jaws respectively in opposed relations to the inner sides thereof the construction indicated in Figure 6 is identical with that shown in Figures 1 to 4 inclusive.

While specific illustration thereof is 15 deemed unnecessary, it will be obvious that the jaws of the holder are adapted for engagement in substantially the manner indicated hereinbefore with other than fabric articles as for example with the wire bales or 20 handles of cans, buckets or like receptacles and in fact with any object of a diameter which is capable of occupying the space between the inner and outer sides of the looped jaws formed at the free ends of the sides of 25 the body loop.

Having described the invention, what is claimed as new and useful is:—

A tag holder consisting of a loop constructed of a single blank of wire having sufficient resilience to provide spring action, 30 the closed end of the loop serving for engagement with a tag, the free ends of the loop being formed to provide complementary jaws of looped form disposed in overlapping relation throughout their lengths which correspond substantially with the width of the main loop, the outer or free legs of the jaw loops having their legs arranged substantially in contact and in parallelism for engagement in common with a portion of the article to which the tag is to be attached, the main loop giving said jaws a spring tendency towards each other, the outer and inner sides of said jaw loops being arranged in intersecting planes oblique to the plane 40 of the body loop.

In testimony whereof he affixes his signature.

JOHN L. KOLBE.
